ABSTRACT OF THE DISCLOSURE

The invention provides basically 2-substituted 1,4-benzodioxanes having the general formula:

where

R is a hydrogen atom, a halogen atom having an atomic number not exceeding 35 or an alkyl or alkoxy group having from one to six carbon atoms,

R¹ is a saturated aliphatic group having one to eight carbon atoms, and

n is an integer from 2 to 6

and acid addition salts of such benzodioxanes. The compounds exhibit an unusual combination of tranquilising, taming and aggression-building activity when administered to rats.

This invention relates to the production of pharmacologically valuable 1,4-benzodioxanes.

The present invention provides a basically 2-substituted 1,4-benzodioxane having the general formula:

in which R is a hydrogen atom, a halogen atom having an atomic number not exceeding 35 or an alkyl or alkoxy group having one to six, preferably one or two, carbon atoms, R¹ is a saturated aliphatic group having one to eight, preferably two to six, carbon atoms and n is an integer from 2 to 6, and acid addition salts of such benzodioxanes.

The substituent R may be present in any of the four available positions in the benzene ring of the 1,4-benzodioxane nucleus, i.e., in the 5-, 6-, 7- or 8-position. The group R may be, for example, chlorine, bromine, methyl, ethyl, methoxy or ethoxy, but is most preferably hydrogen.

The acid addition salt may be any pharmacologically acceptable salt, for example, the hydrochloride, hydrobromide, sulphate, phosphate, acid maleate, acid succinate, acid tartrate or lactate of the said 1,4-benzodioxanes.

The substituent R¹ may be an alkyl group having one to eight, preferably two to six, carbon atoms and may be a straight chain or branched chain alkyl group. When it is a branched chain alkyl group it may be a tertiary-alkyl group. Examples of suitable alkyl groups are methyl ethyl, isopropyl, n-butyl, isobutyl, secondary-butyl, tertiary-butyl, secondary-amyl, tertiary-amyl, n-hexyl, 2,2-dimethyl-n-butyl, 3,3-dimethyl-n-propyl, tertiary-heptyl and tertiary-octyl. Alternatively R¹ may be a cycloalkyl group, for example a cyclohexyl group.

The group -(CH₂)_n is a polymethylene group containing not more than six carbon atoms: it is preferred that this group consist of two, three or four methylene groups.

According to a feature of the invention basically substi-

2

tuted 1,4-benzodioxanes having the above general formula may be prepared by heating a 2-monosubstituted-methyl 1,4-benzodioxane having the general formula:

5 with a mono-substituted alkyl sulphone having the general formula

15 in which formulae R, R¹ and n are as above-defined, one of X and Z is a halogen atom and the other is a primary amino group.

Thus the reaction may be between a 2-aminomethyl-1,4-benzodioxane and a straight chain omega-haloalkyl sulphone in which the second organic group attached to sulphur is a saturated aliphatic group having 1 to 8 carbon atoms, or between a 2-halomethyl-1,4-benzodioxane and a straight chain omega-aminoalkyl sulphone in which the second organic group attached to sulphur is a saturated aliphatic group having 1 to 8 carbon atoms. Both of these reactions lead to the formation of a hydrohalide of the 2-substituted 1,4-benzodioxane. This hydrohalide may be subsequently decomposed by treating the crude product with an acid acceptor. It is preferred to use an inorganic acid acceptor and to carry out the reaction in the presence of a solvent for the base being liberated. After separation of the organic phase containing the free sulphone base, solvent and any low boiling volatile materials can be removed therefrom, the residue taken up in a volatile solvent and treated with a solution of an acid in order to form the corresponding salt.

The 2-aminomethyl-1,4-benzodioxane from which the compounds of the present invention may be obtained include

40 2-aminomethyl-1,4-benzodioxane,
2-aminomethyl-7-chloro-1,4-benzodioxane,
2-aminomethyl-8-methyl-1,4-benzodioxane and
2-aminomethyl-8-methoxy-1,4-benzodioxane.

45 Examples of straight chain omega-haloalkyl sulphones which may be used to prepare the sulphones of the invention include 3-(methylsulphonyl)-n-propyl chloride and bromide, 3-(ethyl-sulphonyl)-n-propyl chloride and bromide, 3-(isopropyl-sulphonyl)-n-propyl chloride and bromide, 3-(tertiary-butyl-sulphonyl)-n-propyl chloride and bromide, 3-(tertiary-amyl-sulphonyl)-n-propyl chloride and bromide, 3-(cyclohexylsulphonyl)-n-propyl chloride and bromide and 4-(ethylsulphonyl)-n-butyl chloride and bromide.

50 The 2-halomethyl-1,4-benzodioxanes from which the compounds of the present invention may also be obtained include

55 2-chloromethyl-1,4-benzodioxane,
2-bromomethyl-1,4-benzodioxane,
2-chloromethyl-7-chloro-1,4-benzodioxane,
2-chloromethyl-8-methyl-1,4-benzodioxane and
2-chloromethyl-8-methoxy-1,4-benzodioxane.

60 Examples of straight chain omega-aminoalkyl sulphones which may be reacted with the 2-halomethyl-1,4-benzodioxanes include tertiary-butyl-2-aminoethyl sulphone, methyl 3-amino-n-propyl sulphone, ethyl 3-amino-n-propyl sulphone, iso-propyl 3-amino-n-propyl sulphone, tertiary-butyl 3-amino-n-propyl sulphone, tertiary-amyl 3-amino-n-propyl sulphone, tertiary-butyl 4-amino-n-butyl sulphone, tertiary-butyl 5-amino-n-pentyl sulphone, tertiary-butyl 6-amino-n-hexyl sulphone and cyclohexyl 3-amino-n-propyl sulphone.

According to an alternative feature of the invention basically substituted 1,4-benzodioxanes having the first general formula given above may also be prepared by a process which comprises reacting a solution in an organic solvent of an acylated 2-substituted 1,4-benzodioxane having the general formula:

(IV)

in which R, R¹ and n are as defined above with a miscible solution of hydrogen peroxide in an organic organic solvent, and thereafter hydrolysing the N-acyl group with a strong acid.

The acylated 2-substituted 1,4-benzodioxanes are in turn prepared by the acylation of basically 2-substituted 1,4-benzodioxanes having the general formula

(V)

in which R, R¹ and n are as above defined. Suitable acylating agents are the acid halides and anhydrides of aliphatic and aromatic monocarboxylic acids such as acetic and propionic anhydrides and benzoyl chloride.

The basically substituted 1,4-benzodioxanes having the General Formula V may be prepared by the reaction of a 2-monosubstituted-methyl 1,4-benzodioxane having the General Formula II with a mono-substituted alkyl sulphide having the general formula

in which R¹, Z and n are as above defined. The preparation of such compounds in which R is a hydrogen atom or an alkoxy group is described in B.D. Auslegeschrift No. 1,118,218: amongst the compounds disclosed therein are

2-(ω -methylmercapto-n-butylaminomethyl)-1,4-benzodioxane,
2-(ω -methylmercapto-n-propylaminomethyl)-1,4-benzodioxane,
2-(ω -ethylmercapto-n-propylaminomethyl)-1,4-benzodioxane,
2-(ω -butylmercapto-n-propylaminomethyl)-1,4-benzodioxane,
5-methoxy-2-(ω -methylmercapto-n-propylaminomethyl)-1,4-benzodioxane,
8-methoxy-2-(ω -methylmercapto-n-propylaminomethyl)-1,4-benzodioxane and

8 - ethoxy - 2-(ω -methylmercapto-n-propylaminomethyl)-1,4-benzodioxane. Those compounds containing in the benzene ring of the 1,4-benzodioxane nucleus a halogen atom or an alkyl group may be prepared by analogous procedures. When produced by this process the compounds of the invention are conveniently obtained as the salts thereof with the acid used to effect the deacylation.

With respect to the oxidation of the acylated 2-substituted 1,4-benzodioxanes with hydrogen peroxide it is preferred to use the same organic solvent for both the acylated 1,4-benzodioxane and the hydrogen peroxide. The normally liquid alkane monocarboxylic acids, especially acetic acid, are suitable for this purpose. The oxidation is an exothermic reaction and it is therefore desirable to add the hydrogen peroxide solution over a period of time so as to prevent the temperature of the reaction mixture exceeding a predetermined maximum of, for example, 50° C. After completion of the reaction the resulting sulphone is conveniently isolated by taking advantage of its solubility in an organic solvent in which the organic solvent used to carry out the reaction is substantially insoluble, the solution freed from any residual hydrogen peroxide, and the produce then hydrolysed with

a strong acid, conveniently after removal of the organic solvent.

The compounds of the present invention have been tested upon mice and rats and have been found to exert 5 muscle relaxant, sedative, tranquilising and taming properties thereon.

An unusual feature of the compounds of the invention is their ability to induce aggressive behaviour in male rats 12 to 24 hours after administration.

At suitable dose levels, the compounds of the invention appear able to induce in rats a characteristic combination of quietness or tameness and self-confidence in the face of aggression. This effect is however biphasic, and is superseded at higher dose levels by relaxant effects.

These compounds in which R¹ is a branched chain alkyl group and n is three have been found to exert muscle relaxant properties in rats for which ED₅₀ is 0.1-1.0 mg. per kilogram bodyweight when administered subcutaneously and 10-100 mg./kg. when administered orally. The approximate LD₅₀ values were >400 mg. per kilogram bodyweight when administered subcutaneously and greater than 400 mg. per kilogram when administered orally.

When administered subcutaneously to mice muscle relaxant properties have been observed for the same compounds for which the ED₅₀ value is about 36 mg. per kilogram bodyweight and the LD₅₀ value is about 285 mg. per kilogram bodyweight: the corresponding values when administered orally being 25 mg./kg. and 400 mg./kg. respectively.

Doses of 10, 20, 40, 60 and 80 mg./kg. in 1% Tween 80 of the products of Examples 1, 2/3, 8 and 9 set out below were injected into rats intraperitoneally daily for 4 days. On the 4th day the rats were tested for the drug's effect on behaviour. 8 male rats were used per dose and a similar number received 1% Tween 80 as a control.

A significant increase in aggressive behaviour over the controls was found in the groups receiving 20 mg./kg. (P<0.025), with the maximum effect at 40 mg./kg. (P<0.05). Doses greater than 80 mg./kg. depressed aggressive behaviour. The approximate acute oral and subcutaneous LD₅₀ in rats is >400 mg./kg.

A single dose of 10 mg./kg. intraperitoneally in a group of ten mice reduced exploratory behaviour when placed in a Y-maze. The results were statistically significant (P<0.02). The approximate acute oral LD₅₀ is 400 mg./kg.: subcutaneously it is 250 mg./kg.

A statistical test for significance between the treated rats and the controls was evaluated by the Mann-Whitney 50 U-test. 5 mg./kg. intramuscularly produced muscle relaxation in the monkey. No adverse side effects were observed.

An unusual feature of the compounds of the invention is their ability to induce aggressive behaviour in male rats 12 to 24 hours after administration.

The following examples illustrate the production of the compounds of the invention:

EXAMPLE 1

60 2-[$(3'$ -tertiary-amylsulphonyl-n-propyl)aminomethyl]-1,4-benzodioxane

2-aminomethyl-1,4-benzodioxane (26.1 g.) and 3-tertiary-amylsulphonyl-n-propylchloride (16.7 g.) were heated at 150° C. for two hours prior to mixing with 2 N caustic soda (40 mls.) and extracted with chloroform (once with 20 mls. and twice with 10 mls.). The chloroform extracts were combined and the combined extracts distilled to a final residue temperature of 220° C. at 0.05 mm. of mercury. 5 N hydrochloric acid (55 mls.) was added to the cooled residue and the mixtures refluxed whilst ethanol (16 mls.) was added, thus giving homogeneity. After cooling, the solution was extracted with chloroform (once with 25 mls. and twice with 10 mls.) and anhydrous diethyl ether (225 mls.) added to the 70 combined chloroform extracts. The mixture was allowed 75 to stand overnight and the ether layer separated and dried over magnesium sulphate. The ether was removed under reduced pressure to give a residue which was purified by column chromatography (silica gel) to give the product as a white crystalline solid.

to stand for one hour and then filtered, the crystalline residue being twice washed with diethyl ether and then dried under reduced pressure to yield the crude hydrochloride of the sulphone (25.9 g.), melting point 124 to 129° C.

Three recrystallisations from isopropyl alcohol gave the pure hydrochloride, melting point 132 to 134° C.

Analysis.—Calculated for $C_{17}H_{26}NSClO_4$ (percent): C, 54.04; H, 7.47; S, 8.49; Cl, 9.38. Found (percent): C, 54.04; H, 7.41; S, 8.29; Cl, 9.32.

EXAMPLE 2

2-[(3'-tertiary-butylsulphonyl-n-propyl) aminomethyl]-1,4-benzodioxane

2-aminomethyl-1,4-benzodioxane (82.5 g.) and 3-tertiary butylsulphonyl-n-propylchloride (50 g.) were heated at 150° C. for 2 hours prior to mixing with 2 N caustic soda (125 mls.) and then extracted with chloroform (once with 60 mls. and twice with 25 mls.). The chloroform extracts were combined, washed with water and distilled to a final residue temperature of 215° C. at 0.1 mm. to give a dark brown oil. 5 N hydrochloric acid (175 mls.) was added to the cooled residue and the mixture refluxed with the addition of charcoal, filtered hot, cooled, scratched and allowed to stand overnight in the ice box. The crystalline produce is filtered and the residue on the filter washed twice with cold 5 N hydrochloric acid then four times with anhydrous diethyl ether. Drying under reduced pressure gave the crude hydrochloride (52.9 g.), melting point 157-160° C.

Recrystallisation from isopropyl alcohol have the product as white crystals, melting point 157 to 160° C.

Analysis.—Calculated for $C_{16}H_{26}NSClO_4$ (percent): C, 52.81; H, 7.20; N, 3.85; S, 8.81; Cl, 9.74. Found (percent): C, 52.91; H, 7.00; N, 4.02; S, 9.02; Cl, 9.68.

EXAMPLE 3

2-[(3'-tertiary-butylsulphonyl-n-propyl)aminomethyl]-1,4-benzodioxane

2-(3'-tertiary-butylthio - n - propyl)aminomethyl-1,4-benzodioxane (18.2 g.) and acetic anhydride (6.7 mls.) were heated on a steam bath under reflux for thirty minutes, the volatile materials evolved were then removed under reduced pressure at 100° C. and the residue dissolved in acetic acid (60 mls.). After cooling to room temperature a mixture of acetic acid (22.5 mls.) and hydrogen peroxide (22.5 mls. of 100 vol.) was added with stirring and cooling at such a rate that the temperature did not exceed 50° C. The mixture was then refluxed for one hour prior to pouring into water (600 mls.) and extraction with chloroform (once with 50 mls. and twice with 20 mls.). The chloroform extracts were combined and then washed with water (thrice with 20 mls.)—a few drops of 20% w./w. sodium sulphite solution being added to the last portion of water until a negative peroxide indication was obtained. After removal of the chloroform under reduced pressure the residual oil was mixed with 5 N hydrochloric acid (60 mls.) and refluxed for nine hours. On cooling and scratching and standing overnight in the ice box, crystals separated: these crystals were filtered off and twice washed with cold 5 N hydrochloric acid, then four times with anhydrous diethyl ether followed by drying under reduced pressure to give the crude product (9 g.), melting point 153 to 156° C.

Two recrystallisations from isopropyl alcohol gave the product as the hydrochloride, melting point 157 to 160° C. Mixed melting point with the product of Example 2 gave no depression.

EXAMPLE 4

2-(3'-isopropylsulphonyl-n-propyl)aminomethyl-1,4-benzodioxane

2-aminomethyl-1,4-benzodioxane (33 g.) and 3-isopropylsulphonyl-n-propyl chloride (18.45 g.) were heated at

150° C. for 2 hours prior to working up as described in Example 2. Drying under reduced pressure gave the crude hydrochloride (16.5 g.), melting point 145 to 148° C.

Recrystallisation from a mixture of isopropanol (70 mls.) and ethanol (20 mls.) gave the product as white crystals, melting point 148 to 150° C.

Analysis.—Calculated for $C_{15}H_{24}NSClO_4$ (percent): C, 51.48; H, 6.91; S, 9.16; Cl, 10.14; N, 4.00. Found (percent): C, 51.40; H, 6.80; S, 9.27; Cl, 10.32; N, 3.78.

EXAMPLE 5

2-(3'-ethylsulphonyl-n-propyl)-aminomethyl-1,4-benzodioxane

2-aminomethyl-1,4-benzodioxane (33 g.) and 3-ethylsulphonyl-n-propyl chloride (17 g.) were heated at 150° C. for 2 hours prior to working up as described in Example 2. Drying under reduced pressure gave the crude hydrochloride (25.9 g.), melting point 167 to 169° C.

Recrystallisation from a mixed solvent of methanol (75 mls.), and ethanol (50 mls.) gave the product as white crystals, melting point 172 to 174° C.

Analysis.—Calculated for $C_{14}H_{22}NSClO_4$ (percent): C, 50.07; H, 6.61; N, 4.17; S, 9.55; Cl, 10.56. Found (percent): C, 50.18; H, 6.63; N, 4.11; S, 9.25; Cl, 10.20.

EXAMPLE 6

2-(4'-tertiary-butylsulphonyl-n-butyl) aminomethyl-1,4-benzodioxane

2-(4'-tertiary-butylthio-n-butyl) aminomethyl-1,4-benzodioxane (15.3 g.) and acetic anhydride (5.6 mls.) were reacted and worked up as described in Example 3. The acylated compound was then treated with hydrogen peroxide and acetic acid, the further treatment and working up also proceeding as described in Example 3. Drying under reduced pressure gave the crude hydrochloride (7.3 g.), melting point 182 to 184° C.

Recrystallisation from ethanol gave the product as white crystals, melting point 186 to 188° C.

Analysis.—Calculated for $C_{17}H_{28}NSClO_4$ (percent): C, 54.04; H, 7.47; N, 3.71; S, 8.49; Cl, 9.38. Found (percent): C, 53.73; H, 7.49; N, 3.56; S, 8.37; Cl, 9.35.

EXAMPLE 7

2-(3'-cyclohexylsulphonyl-n-propyl) aminomethyl-1,4-benzodioxane

2-aminomethyl-1,4-benzodioxane (33 g.) and 3-cyclohexylsulphonyl-n-propyl chloride (22.45 g.) were heated at 150° C. for two hours prior to working up as in Example 2. Drying under reduced pressure gave the crude hydrochloride (33.5 g.), melting point 171-175° C.

Recrystallisation from ethanol gave the product as white crystals, melting point 173-176° C.

Analysis.—Calculated for $C_{18}H_{28}NSClO_4$ (percent): C, 55.46; H, 7.24; N, 3.59. Found (percent): C, 55.66; H, 7.27; N, 3.53.

EXAMPLE 8

2-(3'-tert-butylsulphonyl-n-propyl) aminomethyl-8-methyl-1,4-benzodioxane

2-aminomethyl-8-methyl-1,4-benzodioxane (26.1 g.) and 3-tert-butylsulphonyl-n-propyl chloride (14.9 g.) were heated at 150° C. for two hours and then worked up as in Example 1. Drying under reduced pressure gave the crude hydrochloride (24 g.), melting point 104-134° C.

Recrystallisation from isopropyl alcohol gave the product as white crystals, melting point 147-151° C.

Analysis.—Calculated for $C_{17}H_{28}NSClO_4$ (percent): C, 54.04; H, 7.47; N, 3.71; S, 8.49; Cl, 9.38. Found (percent): C, 54.14; H, 7.38; N, 3.62; S, 8.69; Cl, 9.62.

EXAMPLE 9

2-(3'-tert-amylsulphonyl-n-propyl) amino-methyl-7-chloro-1,4-benzodioxane

2-chloromethyl-7-chloro-1,4-benzodioxane (1.1 g.) and 3-tert-amylsulphonyl-n-propylamine (1.9 g.) were heated at 150° C. for two hours and then worked up as in Example 1. Drying under reduced pressure gave the crude hydrochloride (1.0 g.), melting point 178° C.

Recrystallisation from isopropyl alcohol gave the product as white crystals, melting point 200-202° C.

Analysis.—Calculated for $C_{17}H_{28}NSClO_4$ (percent): C, 49.50; H, 6.35; N, 3.39; S, 7.76; Cl, 17.20. Found (percent): C, 49.71; H, 6.46; N, 3.44; S, 8.04; Cl, 16.96.

EXAMPLE 10

2-(2'-tert-amylsulphonylethyl) amino-methyl-1,4-benzodioxane

2-aminoethyl-1,4-benzodioxane (6.6 g.) and 2-tert-amylsulphonyl ethyl chloride (4.0 g.) were heated at 155° C. for two hours and then worked up as in Example 1. Drying under reduced pressure gave the crude hydrochloride. Recrystallisation from isopropyl alcohol gave the product as white crystals, melting point 186-187° C.

Analysis.—Calculated for $C_{16}H_{26}ClNO_4S$ (percent): C, 52.80; H, 7.20; N, 3.85; S, 8.81; Cl, 9.74. Found (percent): C, 52.45; H, 7.16; N, 3.85; S, 8.64; Cl, 9.69.

EXAMPLE 11

Preparation of 2-(3-tert-amylsulphonyl-n-propyl) amino-methyl-8-methoxybenzo-1,4-dioxan (hydrochloride)

A mixture of 2-chloromethyl-8-methoxybenzo-1,4-dioxan (6.0 g., 0.03 mole) and tert-amylsulphonyl-n-propylamine (10.8 g., 0.06 mole) was heated at 150° for 2 hours. The mixture was cooled, a solution of sodium hydroxide (2.4 g., 0.06 mole) in water (30 ml.) was added and the mixture was extracted with chloroform (3×30 ml.). The solvent was removed by distillation under reduced pressure and unchanged amine was distilled off at 130-150° at 0.5 mm. Hg. The residue was subjected to chromatography on alumina

- (i) eluting with chloroform
- (ii) eluting with ethanol

Hydrochloric acid (8 ml., 50%) was added to the appropriate fraction and the mixture refluxed for 0.5 hr. The mixture was cooled and extracted with chloroform. Anhydrous ether was added to the extract when an oil separated out. This oil was dried overnight in vacuo over phosphorus pentoxide when crystallisation occurred. The solid was recrystallised twice from ethylacetate/ether.

Weight 200 mg., m. 147-150°

Calculated for (percent): C, 53.00; H, 7.41; N, 3.43; S, 7.85; Cl, 8.68. Found (percent): C, 52.54; H, 7.23; N, 3.67; S, 7.58; Cl, 9.01.

We claim:

1. Basically 2-substituted 1,4-benzodioxane having the formula:

where

R is hydrogen, halogen having an atomic number not exceeding 35 or alkyl or alkoxy having from one to six carbon atoms,

25 R¹ is a saturated alkyl and cycloalkyl having one to eight carbon atoms, and

n is an integer from 2 to 6

and pharmacologically acceptable acid addition salts of such benzodioxane.

30 2. Basically 2-substituted 1,4-benzodioxane as claimed in claim 1, wherein R is hydrogen, 7- or 8-chlorine or 7- or 8-methyl, -ethyl, -methoxy or -ethoxy.

35 3. Basically 2-substituted 1,4-benzodioxane as claimed in claim 1, wherein R is a straight chain or branched chain alkyl having from 2 to 6 carbon atoms or cyclohexyl.

40 4. Basically 2-substituted 1,4-benzodioxane as claimed in claim 3, wherein R' is tertiary-butyl or tertiary amyl.

5. Basically 2-substituted 1,4-benzodioxane as claimed in claim 1, wherein n is 2, 3 or 4.

45 6. 2-[3'-tertiary -amylsulphonyl -n -propyl)amino-methyl]-1,4-benzodioxane.
